CLAIM

The ornamental design for a pressurized water shield, as shown and described.

DESCRIPTION

FIG. 1 is a perspective view of the pressurized water shield of the instant invention;

FIG. 2 is a top plane view of the shield;

FIG. 3 is a bottom plane view thereof;

FIG. 4 is a side view thereof, the other side being a mirror image;

FIG. 5 is a front elevational view thereof; and,

FIG. 6 is a rear elevational view thereof.
